CLAIM

The ornamental design for a bait can cover, substantially as shown and described.

DESCRIPTION

FIG. 1 is a top plan view of a bait can cover showing my new design;

FIG. 2 is a bottom plan view thereof;

FIG. 3 is an enlarged right side elevational view thereof; the left side elevational view being identical thereto; and

FIG. 4 is an enlarged sectional view taken along line 4—4 of FIG. 1;

FIG. 5 is a top plan view of a second embodiment of a bait can cover;

FIG. 6 is a bottom plan view thereof;

FIG. 7 is an enlarged right side elevational view thereof; the left side elevational view being identical thereto; and

FIG. 8 is an enlarged sectional view taken along line 8—8 of FIG. 5.
